(57) CLAIM

The ornamental design for a trim strip, as shown and described.

DESCRIPTION

FIG. 1 is a perspective view of a trim strip showing its indefinite length, according to my new design;

FIG. 2 is a left-side of right-side elevational view of the trim strip of FIG. 1, since the two views are mirror images of each other;

FIG. 3 is a front elevational view of the trim strip of FIG. 1;

FIG. 4 is a rear elevational view of the trim strip of FIG. 1;

FIG. 5 is a top plan view of the trim strip of FIG. 1; and,

FIG. 6 is a bottom plan view of the trim strip of FIG. 1.
